DESIGN FOR ROOFING

Norman P. Harshberger, Scarsdale, N. Y., assignor
to Bakelite Building Products Co. Inc., New
York, N. Y., a corporation of Delaware

Application November 19, 1930, Serial No. 37,714

Term of patent 14 years

To all whom it may concern:

Be it known that I, NORMAN P. HARSHBERGER, a citizen of the United States, residing at Scarsdale, in the county of Westchester and State of New York, have invented a new, original, and ornamental Design for Roofing, of which the following is a specification, reference being had to the accompanying drawing, forming part thereof.

In the drawing, showing my new design, Figure 1 is a detail view of the roofing shown in Fig. 2, and Figure 2 is a plan view of the roofing showing my new design, the ends being shown broken away.

I claim:

The ornamental design for roofing, as shown.
NORMAN P. HARSHBERGER.
